234,834

INDICATOR

John H. Cleave, 1357 W. Morris,
Fresno, Calif. 93705

Filed Dec. 20, 1972, Ser. No. 316,895

Term of patent 14 years

Int. Cl. D20—03

U.S. Cl. D96—2

Fig. 1.

Fig. 2.

Fig. 3.

Fig. 4.

Fig. 5.

FIG. 1 is a front elevational view of the indicator showing my new design;

FIG. 2 is a left side elevational view thereof, the right side being identical;

FIG. 3 is a bottom plan view thereof, the top being identical;

FIG. 4 is a rear elevational view thereof;

FIG. 5 is a front elevational view thereof with some of the individual tabs being pivoted to a non-indicating position.

I claim:

The ornamental design for an indicator, substantially as shown and described.
